(57) **CLAIM**

The ornamental design for a combined pestle and mortar lid as shown and described.

DESCRIPTION

FIG. 1 is a front perspective view of the combined pestle and mortar lid showing my new design.

FIG. 2 is an exploded perspective view thereof.

FIG. 3 is a front elevational view thereof; the rear elevation view is a mirror image of the front side.

FIG. 4 is a right side elevational view thereof; the left side elevation view is a mirror image of the right side.

FIG. 5 is a top plan view thereof; and,

FIG. 6 is a bottom plan view thereof.

The broken lines shown in FIG. 6 and the broken lines in the form of a pestle in FIGS. 1 and 2 depict portions of the combined pestle and mortar lid that form no part of the claimed design. The additional broken lines in the form of a mortar in FIGS. 1 and 2 depict environmental subject matter and form no part of the claim thereof.
